UNITED STATES PATENT OFFICE.

WILLIAM SEIDEL, OF WHEELING, ILLINOIS.

BOTTLE WASHING AND SCRUBBING MECHANISM.

No. 854,535.

Specification of Letters Patent.

Patented May 21, 1907.

Application filed March 30, 1906, Serial No. 308,836.

To all whom it may concern:

Be it known that I, WILLIAM SEIDEL, a citizen of the United States, residing at Wheeling, in the county of Cook and State of Illinois, have invented certain new and useful Improvements in Bottle Washing and Scrubbing Mechanism, of which the following is a specification.

The object of this invention is to provide a mechanism for automatically and successively soaking, rinsing and scrubbing bottles used for the transportation of beer, milk or other articles in which it is highly important that the bottles be thoroughly cleansed preparatory to being filled with liquid.

The invention relates to means for carrying the bottles through the different tanks, to the means for filling and emptying the bottles, and to the means for scrubbing the interior of the bottles to remove any sediment or impurities lodged therein.

The invention further relates to the method of actuating the bottle transporting and scrubbing mechanism, and to the means employed for holding the bottles in position in the scrubber and automatically scrubbing the interior of each bottle during its passage through the scrubber.

The invention finally consists in the features of construction and combination of parts hereinafter described and claimed.

In the drawings Figure 1 is a side elevation of the entire mechanism showing the tank with the front walls removed; Fig. 2 an enlarged section taken on line 2-2 of Fig. 1; Fig. 3 a plan view of the entire mechanism; Fig. 4 a cross section taken on line 4-4 of Fig. 1; Fig. 5 a section of the feed chain and rollers; Fig. 6 an enlarged detail of the scrubbing mechanism; Fig. 7 an enlarged view taken on line 7-7 of Fig. 1; Fig. 8 an end view of the mechanism; Fig. 9 a view showing a portion of the carrying trough; and Fig. 10 a fragmentary view showing a portion of the mechanism illustrated in Fig. 6.

The washing and scrubbing mechanism as a whole consists of a soaking tank 1 and a rinsing tank 2, both of oblong shape and open at the top. Extending longitudinally of the tank is a feed box or trough 3 of rectangular formation having a top wall 4, a bottom wall 5, and side wheels 6 and 7 respectively. The soaking tank or trough at its center 8 is inclined sufficiently to allow the bottles fed through the trough to be

filled with water, which is freely admitted into the feed trough through perforations 9 in the walls of the feed trough, and at the center of the trough is located a brush 10, the bristles of which extend down sufficiently to contact the bottles as they are rolled along through the feed trough, which contact serves to remove particles of dirt or sediment adhering to the exterior of the bottles. The bottles are fed along by means of a primary endless chain 11 which passes around sprocket wheels 12 and 13 at the ends of the soaking tank and is then carried on an upward slope around an upper central sprocket wheel 14 and thence back around an intermediate sprocket wheel 15.

The chain at all points follows the direction of the feed trough, which, passing longitudinally through the soaking tank, is provided with a curved end section 16, conforming to the curvature of the sprocket wheel 13, which end section 16 terminates in an upwardly sloping section 17 which extends in reverse direction to the section 3 and is tipped or tilted reversely thereto, as shown in Fig. 2. The sloping section of the feed trough 17 terminates in a curved end section 18 following the curvature of the sprocket wheel 14, which section 18 terminates in a reversely extending sloping section 19, which in turn follows the curvature of the sprocket wheel 15 and terminates in a vertically extending section 20, which connects with the inner end of the longitudinally extending section in the soaking tank. The inner end wall of the feed trough throughout its entire extent is provided with a slot 21, best illustrated in Fig. 9, and the endless sprocket chain is supported so as to travel in substantial alinement with the slot throughout its entire orbit. The sprocket chain, as shown in Fig. 5, consists of a plurality of longitudinally extending links 22 which are pivoted together by means of rods 23 which are outwardly extended on one side of the chain and provided with feed rollers 24, which rollers are entered into the feed trough and roll along the bottom thereof to roll the bottles down through the feed trough, as will be hereinafter explained. The chain travels along the outside of the feed trough, and the rods 23, being of small diameter, easily travel through the continuous longitudinally extending slot in the feed trough.

In addition to the trough hitherto de-

scribed, which may be termed the primary feed trough, is a secondary feed trough, consisting of a lower section 25 which extends from end to end of the rinsing trough 2 and is tilted or tipped at its center 26 in a manner to that hitherto described to the corresponding section of the primary feed trough. The lower section of the secondary trough terminates at its inner end in a vertically extending section 27, which in turn is connected with an upper section 28 which is upwardly inclined from the vertical section 27 and is tilted or tipped in reverse relation to the lower section 25. The section 28 passes through a scrubber 29, to be hereinafter described, and is connected by means of a vertically extending section 30 with the lower longitudinally extending section 25. The secondary feed trough, like the primary feed trough, has extending alongside of it an endless feed chain 31, in all respects similar to that hitherto described, which chain is carried around upper and lower sprocket wheels 32 and 33 respectively at the inner end of the rinsing tank and sprocket wheels 34 and 35 at the outer end of the rinsing tank, the secondary feed trough being rounded to conform to the curvature of the sprocket wheels carrying the chain. The inner upper corner 36 of the secondary feed trough lies immediately beneath and is connected with the end section 18 of the primary feed trough, and, at the point of juncture, the wall between the two troughs is cut away to provide a discharge opening 37, immediately beneath which is a soft pad 38 which allows the bottles to drop from the primary feed trough into the secondary feed trough, as best shown in Fig. 9. The bottles are initially inserted into the primary feed trough through an opening 39 immediately above the sprocket wheel 15, and the bottles are finally discharged from a chute 40 extending downwardly from the upper section 28 of the secondary feed trough, as shown in Fig. 1.

The scrubber, best illustrated in Fig. 6, comprises an inner drum 41 mounted upon a shaft 42 upon which is also mounted a sprocket wheel 43 carrying the secondary sprocket chain. The drum 41 extends outwardly from the secondary feed trough, a portion of the roof of which is shown broken away in Fig. 6, with dotted lines indicating the position of the bottles. The drum is provided with a circumferentially extending rib 44 provided on its periphery with a toothed rack 45 which meshes with a sprocket wheel 46 mounted on a shaft 47 within journal boxes 48 on a stationary outer shell 49. The shaft 47 has also mounted thereon a gear wheel 50 which is constantly rotated by the intermeshing of the gear wheel 46 with the rack 45, and said gear wheel 50, which maintains a fixed position, is adapted to mesh at suitable intervals with gear wheel clutch sec-

tion 51 which are rotatably mounted on the ends of tubular sleeves 52 which are passed through and fixedly mounted within the rib 44 at the outer end, and at the inner end are secured within an end flange 53 at the inner end of the drum 41, which drum is provided with a closing end 54 having in its center a hub 55. The outer end of the drum is likewise inclosed by means of an end wall 56 having in its center a hub 57. The clutch section 51 is intended to engage with a clutch section 58 which is fixedly secured to a brush tube 59 which surrounds an inner guide rod 60 fixedly secured at its outer end to a flange 61 corresponding in size and shape with the flange 53 at the opposite end of the drum. The brush tube 59 has inserted thereinto at its inner end a plurality of fine spring steel rods 62 adapted to enter the mouth of a bottle, and a reciprocating motion is imparted to the brush tube 59 by means of a rack 63, slidably mounted on the guide rod 60, the teeth of which rack mesh with the teeth of a gear wheel 64, which in turn mesh with a fixed rack 65 on the outer face of the drum. The gear wheel 64 is mounted on a shaft 66 which is carried between side arms 67 of a yoke having a cross head 68 provided with a flange 69 which enters a cam groove or track 70 which is formed on the inner face of the outer stationary cylindrical casing 49 which surrounds the outer end of the inner drum. The cam track, as shown in dotted lines, extends in a diagonal direction, so that a portion of the track tends to give a forward thrust to the cross head 68 and gear wheel 64 carried thereby, and a portion of the track tends to retract the cross head and gear wheel. The yoke, carrying the gear wheel, straddles the rack 63 which is slidably mounted within the yoke so that, as the cam track directs the movement of the yoke, the gear wheel, which at all times meshes with the fixed rack 65, will tend to give a forward thrust or rearward retraction of the rack and the brush tube and brush rods carried thereby.

At the inner end of the fixed guide tube 52 is a tubular sealing neck 71 which terminates in a flaring mouth 72 adapted to receive the mouth of a bottle, and said mouth projects into the secondary feed trough a sufficient distance to have the bottle mouth firmly and tightly inserted thereinto. The feed trough is provided with a cam plate 73 on the side of the trough adjacent to the sealing mouth, the end of which cam plate is in substantial alignment with the outer edge of the sealing mouth and serves to thrust back the bottles sufficiently for the bottle mouth to clear the edge of the sealing mouth preparatory to the sealing operation. On the opposite side of the trough is a second cam plate 74 which extends a considerable distance along the wall of the trough and serves, after the bottle has been given a backward thrust, to give

it a forward or reverse thrust into the sealing mouth, in which position it is held during a considerable period of time.

In order to permit the drum 41 to be operated at will, it is loosely mounted upon the shaft 42 and is adapted to have rotation imparted thereby through the medium of a clutch member 75 fixedly secured to the shaft, which clutch member is operated by means of a lever 76 pivoted at one end between ears 77 secured to the inner wall of the trough, which arrangement enables the endless feed chain to constantly rotate the shaft and enables the drum to be clutched or unclutched at will.

It will be understood that the brush mechanism and gear and rack mechanism heretofore described are duplicated at suitable intervals around the periphery of the drum so that the bottles, fed to the scrubber by means of the feed chain and rollers, will each be scrubbed out on its interior, during its progress through the scrubber. In case it is desirable to sterilize the bottles in the soaking tank, such sterilization can be done by means of steam admitted through steam pipes 78 adapted to receive steam from any suitable source of supply.

Power is imparted to the primary and secondary endless feed chains by means of a longitudinally extending power shaft 79 provided with fast and loose pulley wheels 80 at one end and provided at its opposite end with a worm 81 which meshes with worm gear wheels 82 and 83 respectively, the former of which imparts rotation to the sprocket wheel 14 and the latter of which imparts rotation to the sprocket wheel 32.

In use the bottles are fed through the opening 39 between the rollers which are constantly moving along the primary feed trough, and the diameter of the bottles is sufficient to substantially fill the interior of the feed trough which causes the bottles to be held between the rollers and carried down along the feed trough and into the soaking tank. The bottles rest against the floor of the trough and are rolled along by the rollers, being tilted somewhat as they approach the center of the tank by reason of the tilt or slope of the trough, which allows the bottles to be filled with water and the air expelled, and as the bottles are rolled under the brush 10, any dirt or particles or sediment adhering to the surface of the bottles will be brushed off. The bottles are carried through the soaking tank by means of a chain and are then elevated into the inclined upper section of the primary feed trough which is tilted in a direction opposite to that of the lower section of the feed trough, which tilt of the upper section of the trough depresses the bottle mouths and permits the water, hitherto admitted into the bottles, to flow back along the trough and into the tank

again. After the bottles are carried around the curved end section 18 of the primary feed trough, they fall by gravity through the opening 37 at the juncture of the primary and secondary troughs, striking upon the soft pad 38, which prevents breakage, after which they are carried forward between the feed rollers of the secondary feed chain into and through the soaking tank, in which tank they are again filled with water, after which they are carried up to the scrubber, each bottle being entered into one of the sealing mouths of the scrubber, as hitherto described.

The bottles are sealed, as shown at the lower side of Fig. 6, in which position the brush tubes and brush rods are retracted to permit the insertion of the bottle mouth, but after the bottle has been sealed it is carried around with the brush mechanism until the brush tube is thrown forward into the position shown at the upper side of Fig. 6, which causes the flexible brush rods or wires to be thrust forward into the body of the bottle and against the end thereof, which causes the brush wires or rods to spread within the body of the bottle and abut against the sides of the bottle. With the brush rods thus spread or expanded within the bottle, the brush tube will be momentarily revolved by the intermeshing of the teeth of the gear wheel 50 with the teeth of the gear clutch section 51, which, when brought into mesh with the gear 50, will be likewise clutched to the slidably geared section 58, to which the brush tube is fixedly secured. This gives a rapid, though momentary revolution, to the expanded brush wires within the bottle, which serves to thoroughly scrub out the interior of the bottle and loosen up any sediment or dirt which may be lodged therein. After the scrubbing operation above described, the bottles are unsealed and carried along the upper section 28 of the secondary feed trough and discharged through the chute 40.

From the foregoing description it will be seen that the several steps in the operation of washing the bottles are all performed automatically and continuously, the bottles being fed entirely through the machine without the necessity for any handling or supervision. The bottles are scrubbed both on the outside and inside during their passage through the mechanism, so that after being discharged they will be thoroughly cleansed and ready for use. The water in the initial or soaking tank will be all drawn out of the bottles, together with such dirt and sediment as may be dissolved thereby, prior to the admission of the bottles in the rinsing tank, so that the bottles will be in a fairly clean condition prior to their immersion in the rinsing tank.

What I regard as new and desire to secure by Letters Patent is:

1. In a machine of the class described, the combination of a soaking tank, a rinsing

5 tank, a trough extending through the soaking tank, a trough extending through the rinsing tank and connecting with the trough in the soaking tank, and feeding mechanism for carrying the bottles through the two troughs, substantially as described.

10 2. In a machine of the class described, the combination of a soaking tank, a rinsing tank, a trough for each of the tanks, each of the troughs having a lower section within the tank and an upper section above the tank, the two troughs being connected, and endless chains, one for each of the troughs, adapted to carry the bottles through the trough, substantially as described.

15 3. In a machine of the class described, the combination of a soaking tank, a rinsing tank, a trough for each of the tanks, each of the troughs having a lower section within the tank and an upper section above the tank, the two troughs being connected, and endless chains, one for each of the troughs, said chains being located outside of the troughs and provided with rollers extending into the troughs for rolling the bottles through the troughs, substantially as described.

20 4. In a machine of the class described, the combination of a soaking tank, a rinsing tank, a trough for each of the tanks, each of the troughs having a lower section in the tank and an upper section above the tank, the trough in the soaking tank being provided with an extension overhanging and connected with the trough in the rinsing tank for allowing the bottles to fall by gravity from one trough to the other, and endless chains, one for each of the troughs, adapted to carry the bottles through the troughs, substantially as described.

25 40 5. In a machine of the class described, the combination of a soaking tank, a rinsing tank, a trough for each of the tanks, each of the troughs having a lower section in the tank and an upper section above the tank, the trough in the soaking tank being provided with an extension overhanging and connected with the trough in the rinsing tank

50 for allowing the bottles to fall by gravity from one trough to the other, and endless chains, one for each of the troughs, said chains being located outside of the troughs and provided with rollers extended into the troughs for rolling the bottles through the troughs, substantially as described.

55 6. In a machine of the class described, the combination of a soaking tank, a rinsing tank, an endless trough for each of the tanks, each trough having a lower section within the tank and an upper section above the tank, one of the troughs being provided with an upwardly sloping extension having near its extremity and immediately above the trough in the other tank, an orifice for discharging bottles from one of the troughs into the other, and means for feeding the bottles 60 successively through the troughs, substantially as described.

7. In a machine of the class described, the combination of a soaking tank, a rinsing tank, an endless trough for each of the tanks, one of the troughs being provided with an extension overhanging and opening into the other trough, a scrubbing mechanism located within and coacting with the last mentioned trough, and means for carrying the bottles 70 successively through the two troughs and the scrubbing mechanism, substantially as described.

75 8. In a machine of the class described, the combination of a soaking tank, a rinsing tank, an endless trough for each of the tanks, one of the troughs being provided with an extension overhanging and opening into the other trough, a scrubbing mechanism located within and coacting with the last mentioned 80 trough, and an endless chain for each of the troughs, provided with feeding rollers for carrying the bottles through the troughs and through the scrubbing mechanism, substantially as described.

WILLIAM SEIDEL.
